FRAMING FOR WALLS AND BUILDINGS

William S. Thomson, Evanston, Ill.

Application May 23, 1933, Serial No. 672,387

3 Claims. (Cl. 189—1)

My present invention relates to improvements in framing for walls, buildings and the like.

My framing comprises studs or units each consisting of two parallel flanges connected together by a web having an expanded or otherwise formed latticed median portion. The studs may be made of iron, steel, or other suitable material. Preferably the two flanges of the individual studs extend oppositely from the web thereby making what may be conveniently termed a Z-shaped stud, so-called because its transverse section resembles a Z.

I assemble these Z-studs in different ways relatively to one another, for example with the flanges of adjacent studs in face to face or parallel relation or with the webs of the adjacent studs partially overlapping one another.

In another aspect of my invention, I am able to use stud-units in my framing which are channel shaped in cross section as distinguished from Z-shaped; and when I use said channel studs I combine them with their web portions partially overlapping one another; although in the case of a thin wall for example a partition, they may be combined with their flanges in face to face or parallel relation.

Whichever assembly arrangement is employed, I unite the studs by bolting, riveting, welding or keying them together; and in addition I bolt, rivet, weld or key them at their ends to sills or to transverse members.

The studs may run up continuously, except for the door and window openings, for a number of stories of the house or building; but I prefer to use a separate set of studs at each story. Each stud at its ends is provided with lugs either integral or non-integral with the body of the stud. These lugs preferably extend from the flanges at right angles to the longitudinal axis of the stud and adjacent the web. The lugs serve to bolt, rivet or weld the first story studs to horizontal metal sills mounted on the foundations of the building. They also serve to unite the studs of an upper story to those of a lower story. The inter-story sills rest upon the lower story studs and underlie the upper story studs with the lugs of the two sets of studs united to or connected through the web of the sills.

The sills of course support the joists and the flooring, the walls and the roof of the building.

I prefer channels for the sills; and these have solid webs that is to say, their webs are non-expanded or non-latticed. Preferably, the webs of these sills are wide enough between flanges to overlie or underlie as the case may be, the flanges

of all of the studs individually and collectively. The sills at the corners of the building preferably come together on mitre joints.

Furring strips or members for attaching the walls and wall structures to the framing are supported between the abutting flanges of adjacent studs by the same bolts or rivets that unite the studs. In lieu of or in addition to said furring strips, I provide rows of holes in the stud flanges and solid portion of web for the attachment of wires or lugs or other suitable devices for tying or securing the walls and wall structures to the built-up structure or framing.

At the sides, top and bottom of the door and window openings, I provide channels or other members in which are secured wood strips for nailing or otherwise suitably securing the usual door and window frames thereto. The channels or other members themselves are secured by bolts or otherwise to the adjacent studs and to suitable interconnecting horizontal members.

Where studs are omitted, for example above and below window and door openings, I substitute suitable structural frame-work secured to the adjacent studs and sills and strengthening them.

It will be noted that each stud in my framing is a truss structure complete in itself having two load carrying members connected by a web having a median open-work or latticed portion able to resist horizontal loads and forces. Also in my system of framing, additional strength and stability are obtained when the stud units are combined and united and this is especially so when they are united in the overlapping relation previously referred to.

The Z-type stud has special advantages as follows. For any given thickness of metal the area of section of the load bearing members, required for strength, can be obtained with greater economy in the Z-shape than with other shapes whose periphery is longer. In compression members, the thickness of metal has an important significance in that, if it is too thin, buckling may occur. Hence if a certain minimum thickness of metal is to be maintained, the section with the shortest periphery to contain a given area, is the most economical. As stated, the Z-shape has this advantage.

At corners, the Z-shape has the further advantage in that one of the flanges of a stud is always available for attachment to the solid web portion of the adjacent corner stud.

In the production of stud-units, it is extremely desirable that their design or form be symmetri-

cal so that they may be used interchangeably in different portions of the framing of the structure or be capable of reversal about either a horizontal or vertical axis of symmetry, without impairing their usefulness as structural members. The drawings show Z-units of both the expanded and welded type illustrating the principles of symmetry and reversibility. A channel unit is also shown embodying this principle.

10 In bearing-walls, aside from structural considerations, it is of practical advantage to have the web members located at the center of the wall structure. This arrangement divides the wall space into two equal parts, one or both of which 15 may be utilized to receive an insulating medium, or one may act as an air space in providing further insulation. The webs of the studs provide a convenient backing for the insulating medium. Detail of this construction using Z-studs is 20 shown in Fig. 6 and using channel studs in Fig. 12.

In shipping, the shape of the object is of importance both in the efficiency with which it may be handled and in regard to the space occupied in the carrier. A plurality of Z-shaped studs may 25 be nested together to form a compact package occupying a minimum amount of space.

In connection with my framing, it should be noted that the outer wall covering of the building may be constructed of various materials such as 30 wood, brick, stone, or stucco or of metal sheets, keyed, tied, bolted or welded as the case may be, to the framing. Likewise the inner wall covering of the structure may be of any material suitable for that purpose. In fact, there is no limitation 35 as to the type or character of inner and outer wall coverings that may be applied to my framing.

I will now describe a preferred form of my invention with some modifications in order to illustrate specific embodiments of the invention, but without limiting the invention to said 40 illustrative embodiments, especially as to the details thereof, except as same may be defined in the appended claims.

In the drawings:
45 Fig. 1 shows in perspective a Z-stud usable with the invention.

Fig. 2 is a section thereof on line 2—2 in Fig. 1.
Fig. 3 is an end view of this Z-stud unit.

Fig. 4 is a perspective view on a larger scale of 50 fragments of two of said studs abutted flange to flange and having integral lugs.

Fig. 5 is a sectional view as if taken on the line 5—5 in Fig. 4 but illustrating a modification wherein the lugs are non-integral with the 55 flanges.

Fig. 6 is a combined horizontal sectional and plan view through the corner of a house or building showing a plurality of the unit studs of the preceding figures combined and built together 60 with other elements.

Fig. 7 is a front elevation on a smaller scale of one side of said corner namely the lower side in Fig. 6, the walls being omitted to show the framing.

65 Fig. 8 is a vertical sectional view on an enlarged scale on the line 8—8 in Fig. 7.

Fig. 9 is a horizontal sectional view on the line 9—9 in Fig. 8.

70 Fig. 10 is a horizontal sectional and plan view on the line 10—10 in Fig. 7.

Fig. 11 is a view similar to Fig. 6 on a smaller scale and shows an overlapping assembly of the Z-studs.

75 Fig. 12 is the same kind of a view but embody-

ing channel sectioned studs assembled with overlap.

Figs. 13 and 14 show a modification of the stud wherein the openwork webbing consists of a separate, formed strip or rod, Fig. 14 being an elevational fragmentary view of said modified stud, and Fig. 13 being an enlarged transverse sectional view of same.

Referring now to the illustrative embodiments, Figs. 1 to 4 show one preferred form of stud or unit designated generally by the numeral 10 usable in my framing. The cross sectional and end views Figs. 2 and 3 show why the term Z-stud conveniently designates this unit. Each stud consists of two flanges 12, projecting in opposite directions from the opposite edges of a connecting web which latter consists of two solid marginal portions 14 connected by a latticed or openwork portion 16. This latticed portion may be made by appropriately slitting and expanding the original solid web in any well known or preferred manner; or as in the stud 18 of Figs. 13 and 14 also within my invention, which stud is of the non-integral type, the latticed portion of the web consists of a separate strip 20 formed as shown and welded or otherwise securely attached at points as shown to a pair of angle members 22.

As shown in Fig. 12, and as will be explained later, channel sectioned studs 24 may be used in carrying out my invention in one of its modifications. These channel studs will also have latticed or openwork webs which may be of the integral type as in Fig. 1 or non-integral as in Fig. 14.

The following details apply or may apply to whichever type of stud is used. The upper and lower ends of the two flanges of each stud are or may be tapered as shown at 26 for the purpose which will hereinafter appear and which briefly is so that the studs will fit between the flanges of a channeled sill 28 as shown in Fig. 8 with the flanges of the sill flush with the edges of the stud-flanges.

Perforated lugs 30 either integral as in Figs. 1 to 4 or non-integral lugs 30a as in Fig. 5 are shown on the flanges at the upper and lower ends of the studs. These lugs extend from the flanges at right angles to the longitudinal axis of the given stud and adjacent its web. Series of holes 32 are provided in the stud-flanges and another series of holes 34 in the solid portions of the webs 50 for bolting or riveting the studs together by bolts or rivets 66 and for attaching means for anchoring the walls to the framing.

The horizontal sectional view in Fig. 6 through the corner of a building embodying my frame 55 shows a plurality of the Z-studs 10 assembled and bolted, welded or riveted together flange to flange by bolts, welds or rivets 66 in the aligned flange holes. The furring strips 36 consist of thin flanged plates which may be Z-shaped in cross 60 section or channeled or merely L-shaped, and are referred to herein under the designation "furring strips" which in Fig. 6 are shown clamped between the flanges of the studs with the flanges of the furring strips located at the inside faces 65 of the walls 38 and 40. The furring strip flanges have series of holes 42 for attaching and anchoring said walls 38 and 40 by any well known or preferred wall attaching and anchoring means to 70 the framing.

This construction provides spaces between the framing and the walls 38 and 40 useful in various ways. For example, for insulating air spaces 44, also spaces to receive insulating material 46, 75

and spaces to receive and pass plumbing pipes, electrical conduits, etc.

Fig. 7 is an elevation of the lower part of Fig. 6 omitting the front wall 38 from Fig. 6 so as to show the framing. This Fig. 7 shows two stories of the structure together with a door opening 48 and a window opening 50 and is typical of the way the framing is assembled and built up for the entire building. In said Fig. 7 the lower ends 10 of the first story studs 10 are secured to a structural sill 28 which in turn has its support and anchorage on the foundation wall 52. Fig. 6 shows how the sills 28 meet at the corner on a mitre joint 28a and how the lugs 30 on the studs 15 serve to secure them to the solid web of the sill upon which the studs rest.

Fig. 7 shows the flanged side of the channeled sill 28. This sill straddles the upper ends of the lower story studs and support the upper story studs as is well shown in the enlarged sectional view, Fig. 8, taken on the line 8-8 in Fig. 7. It shows the assembly of the inverted channeled sill 28 and the tapered flange ends 12 of the upper and lower studs; and further shows the lugs 30 of the 20 said studs and the intervening web of the sill secured together by the bolt 54. It also shows upper and lower furring strips 36. Fig. 9 is another showing of the same parts from another point of view, the same being a horizontal section on the line 9-9 in Fig. 8.

It will be understood from the foregoing that the web of the sills 28 is made wide enough for attachment to all the flanges of the adjacent studs.

Figs. 8 and 9 show how by tapering the flanges 35 of the studs at 26, economy in width of the sills is obtained whereby the sides of the sills are substantially flush with the edges of the stud flanges.

Fig. 6 shows how at the corners of the building, the outer walls 38 forming said corners are 40 both properly anchorable to the framing first by the outwardly extending flange of one of the studs and secondly by an L-shaped furring strip 36 clamped between the web of that stud and the flange of the adjacent corner stud.

The door and window openings 48 and 50 are 45 formed by omitting the studs and filling in the spaces at the top of the doors and at the top and bottom of the windows with structural framework 56, Fig. 7, appropriately secured to the adjacent portions of the studs and sills.

The door and window openings thus formed are fitted on all sides with channels containing nailng strips to which the door and window frames can be secured. These channels designated at 55 58, Figs. 6 and 10, are shown secured by bolts 60 to the flanges of the adjacent studs. The nailng strips 62 are shown secured by bolts 64 to the channels.

Fig. 11 shows how the Z-studs may be assembled and united in a different way, namely, with the web of each stud partially overlapping the web of an adjacent stud. The uniting bolts or rivets are shown at 66, although of course welds

may be used instead. The lugs 30 of the studs will be bolted as before to the web of the sills 28. In this assembly the holes 32 in the stud flanges serve for the attachment of the means by which the walls are anchored to the framing, thereby making furring strips 36 unnecessary except that the latter may be used at the corners of the building as indicated at 36 in Fig. 11. This overlapping assembly of the Z-studs shown in Fig. 11 obviously imparts improved strength and 10 rigidity to the framing due to the series of spaced flanges connected by each overlap.

Fig. 12 show the overlap assembly of Fig. 11 applied to channel sectioned studs designated in general by 24, which are also well adapted to this manner of assembly. These channel studs have or may have the same lugs 30 as the Z-studs, also the same tapered ends for cooperation with the sills 28, also the same webs with solid side portions 14 and latticed median portions 16 and the same 20 series of holes through the flanges and solid web portions for securing the studs to one another and for points of attachment in connection with the anchoring of the walls to the frame.

It will be understood that variations may be 25 made in the foregoing without departing from the scope of the invention as expressed in the appended claims.

What I claim is:

1. Framing for walls and buildings whose vertical members comprise stud-units, each consisting of two substantially parallel flanges projecting oppositely relatively to each other from opposite edges of a slotted connecting web expanded in the plane of said web, said units being assembled and connected together with their webs occupying a median zone of the framing and with the flanges of the studs projecting some on one side and some on the other side of said zone.

2. Framing for walls and buildings whose vertical members comprise stud units, each consisting of two substantially parallel flanges projecting oppositely relatively to each other from opposite edges of a slotted connecting web expanding in the plane of said web, said units being assembled and connected together with their webs occupying a median zone of the framing and with the flanges of the adjacent studs face to face and projecting some on one side and some on the other side of said zone.

3. Framing for walls and buildings whose vertical members comprise stud-units, each consisting of two substantially parallel flanges projecting oppositely relatively to each other from opposite edges of a slotted connecting web expanded in the plane of said web, said units being assembled and connected together with their webs partially overlapped and occupying a median zone of the framing and with the flanges of the studs projecting some on one side and some on the other side of said zone.

WILLIAM S. THOMSON.
